Attorney.

UNITED STATES PATENT OFFICE.

AZEL CLARENCE HOUGH, OF JANESVILLE, WISCONSIN, ASSIGNOR TO HOUGH SHADE CORPORATION, OF JANESVILLE, WISCONSIN, A CORPORATION OF CONNECTICUT.

SCREEN, SHADE, AND THE LIKE.

1,218,556.

Specification of Letters Patent.

Patented Mar. 6, 1917.

Application filed March 28, 1916. Serial No. 87,354.

To all whom it may concern:

Be it known that I, AZEL CLARENCE HOUGH, a citizen of the United States, and resident of Janesville, county of Rock, and 5 State of Wisconsin, have invented an Improvement in Screens, Shades, and the like, of which the following description, in connection with the accompanying drawings, is a specification, like letters on the drawings 10 representing like parts.

My present invention is an improved screen, shade, or the like, with provision for ventilation therethrough.

My invention is an improvement in the 15 woven type of screen as distinguished from the Venetian blind type of screen or shade, wherein slats or wooden members were movable by hand to render the shade open or closed. Such prior wooden shades or screens 20 are very expensive and cumbersome to make, requiring individual fastenings for each slat, and quickly getting out of order and presenting a structure which is difficult or impossible to roll up compactly from either 25 end. The woven screen, on the contrary, being made quickly, economically and as a fabric with transverse slat members and longitudinal warp cords or strands, has almost entirely supplanted the more cumbersome and 30 expensive Venetian blind type of screen, but heretofore it has been presumed to be impossible to make a woven screen structure with provision for ventilation through any portion of it. My present invention solves 35 this problem and enables a ventilating woven screen to be economically and commercially manufactured.

In my development of the art of manufacturing porch shades and screens by weaving, 40 such for example as shown in my prior Patent No. 748,734, I have produced a screen formed of slats tightly woven together and yet of suitable flexibility to be readily rolled up from either end, and I prefer to utilize 45 my present invention in a woven screen of this type. Also I prefer to form such a screen with one or more ventilating portions or sections, while utilizing the type of weaving explained in said patent for the remaining 50 portion of the shade. Thus I produce a woven shade with a close section for a predetermined distance and with one or more open or ventilating sections, resulting in the combination of a close woven portion and a

ventilating portion. In forming the ventilating portion, different methods may be employed and differing constructions utilized, the important feature in my present invention consisting in the combination of a closely woven or non-ventilating section and 60 an open or ventilating section in a woven porch shade or screen. Such ventilating section or sections may be at any predetermined point and of any suitable extent desired, for example, at the upper or top portion of the screen and at the extreme lower or bottom portion, to facilitate the circulation of air and secure the advantages of ventilation through the screen at predetermined sections. It is, of course, important 70 in a shade or screen of this type to have the screen closely woven to exclude the sun's rays and effectively constitute a satisfactory screen, while securing a strong yet flexible construction. The provision of a ventilating 75 section at the upper portion of the screen, for example, is not objectionable in use, while enabling the free flow of air and thus create or stimulate air circulation and provide the desired cooling effects of ventilation. 80 While I mention, specially, a close weave for the main or screen portion of the shade, such as the close weave illustrated in my said prior patent, it will be appreciated that my invention is not limited thereto, but contemplates the provision of a relatively close 85 section in the screen, and a relatively open ventilating section at a predetermined position and of a predetermined proportion of the screen, also a plurality of such ventilating sections in the screen, when so desired.

In the formation of the ventilating section, it will be understood that I am not limited to any particular amount of spacing for ventilation, nor any particular weave, nor 95 to any proportion of ventilating and non-ventilating section. In fact, the ventilating constructions herein shown for illustrative purposes may be utilized advantageously for the entire screen construction, although 100 I contemplate employing the same only as ventilating sections in connection with a relatively non-ventilating portion of a screen as above explained.

Such ventilating construction may be 105 formed in a variety of ways, for example, by weaving the screen with a part relatively close or tight and the ventilating section

relatively loose or open so that the slats may hang separated from each other to provide the desired extent of ventilation; or the ventilating section may be woven with the slats forming it held in predetermined spaced relation, as by twisting the warp cords one or more times to insure the space between the slats, or by forming the slats relatively thick or square, so that the simple weaving will necessarily enable sufficient length in the warp cords between adjacent slats to be left so that the natural stretch or weight of the shade or screen will open the slats in the ventilating section.

Further features of the invention, details of construction and novel combinations of parts will be hereinafter more fully pointed out and claimed.

Referring to the drawings illustrating a woven screen embodying my invention:

Figure 1 is a plan view of a woven screen having a plurality of ventilating sections, one section at the top, one section at the bottom, and the third intermediate section between the two;

Fig. 2 is a cross sectional view of the line 2—2 of Fig. 1;

Figs. 3 and 4 are side and cross-sectional views respectively of a modified form of ventilating section and Figs. 5 and 6 are plan views and cross-sectional views respectively of a further modified form of ventilating construction.

For illustrative purposes I have shown my present invention of a shade or screen with ventilating sections as utilizing the "standard weave," now well known in the trade, of my said prior patent, to which reference is made for further details and advantages of the same.

Referring to Figs. 1 and 2, the shade there shown comprises a plurality of wood slats or weft units, united by woven warp cords. The warp cords 1 are preferably doubled at each end portion of the slats and one or more single warp threads 2 are applied throughout the width of the screen, depending upon the size and strength desired. The slats comprising the relatively close and tight woven or non-ventilating section 3 may be of any suitable width, and the slats 4 constituting the ventilating sections are preferably of slightly narrower formation, although this is entirely optional. Reinforcing and retaining strips 5 and 6 at the top and bottom of the screen are provided, as usual, and I also prefer to apply similar retaining strips 7 and 8 where a ventilating section is formed in the screen, although these additional strips 7 and 8 are optional.

In the screen illustrated in Figs. 1 and 2 I show three ventilating sections, but it will be readily understood that one section only may be utilized, or a larger number if desired. In forming such ventilating

sections I am enabled to use, advantageously, the weaving of the warp cords 1 and 2 by giving to the same a twist, between the ventilating slats 4, as illustrated at points marked 9 and 10 and as clearly shown in the drawings. Such twisting of the warp cords serves not only to space the slats 4 equally and to a predetermined extent throughout the ventilating section, but also acts to firmly and securely bind and hold the slats thus spaced. While a loose weaving throughout the ventilating section might be sufficient in many cases, yet such a loose weaving would not, ordinarily, hold the slats firmly in their respective positions, but might permit lateral displacement or "end chase."

A plurality of such twistings may be employed as illustrated in Figs. 3 and 4, at 11 and 12, thus permitting additional spacing of the slats in a ventilating section. Variation in the spacing may also be regulated by the size of the cord employed.

In Figs. 5 and 6 I have illustrated a still further modification of the construction suitable for a ventilating section. In this form the ventilating slats 13 are formed of a sufficient width so that the woven cords 15, in spanning the thickness of the slats 13, will give sufficient length to permit a substantial stretching of the slats from each other when suspended. With the slats 13 relatively thick or for example square in cross section, this ventilating feature is attained. A still further advantage of the form shown in Figs. 5 and 6 is that such relatively thick slats prevent the sun's rays from slanting through and rain from driving therethrough to the annoyance of persons behind the screen. As the ventilating section will ordinarily be at the extreme top or bottom of the shade, such thick slats will effectually preserve the continuity of the shading construction throughout the entire length of the screen until the sun's rays are substantially level, when, of course, they would penetrate only at the extreme top and bottom of the shade out of range and at such times the sun's rays are unobjectionable.

It will be understood, that, while I prefer to combine the close weave and the open weave for the ventilating section, such open weave including the twisting of the warp cords or otherwise, I am not limited thereto, but claim broadly the combination of a ventilating portion and non-ventilating portion. The utilization of my standard weave with a weaving construction for the ventilating section enables both to be readily adapted in the process of manufacture and lends itself advantageously to uniformity and elegance of product. It is, however, within the scope of certain of the following claims, to utilize any form of weaving or

connection in the non-ventilating portion of the screen and an entirely different means of connection for the slats in the ventilating section.

5 My invention is further described and defined in the form of claims as follows:

1. A woven screen of the kind described, having a ventilating portion and a non-ventilating portion, said non-ventilating 10 portion comprising transverse slat members, warp strands woven tightly about said members, separating said slats only by the compressive thickness of the warp strands, said ventilating portion comprising a plurality 15 of slats so woven by the warp strands as to be spaced apart a distance greater than the thickness of said warp strands, whereby a woven screen having a woven portion permitting the passage of air currents there- 20 through is provided.

2. A woven screen of the kind described, having a plurality of ventilating portions separated by a plurality of non-ventilating portions, each non-ventilating portion comprising transverse slat members, warp 25 strands woven tightly about said members separating said slats only by the compressive thickness of the warp strands, each ventilating portion comprising a plurality of 30 slats so woven by the warp strands as to be spaced apart a distance greater than the thickness of said warp strands, whereby a woven screen having woven portions per-

mitting the passage of air currents there-through is provided.

3. A woven screen of the kind described, comprising a ventilating portion and a non-ventilating portion, said non-ventilating portion consisting in slats held closely together by woven warp strands interlaced 35 about said slats, said ventilating portion having the slats so woven by said warp strands as to be substantially spaced from each other and from the end slat of said non-ventilating portion, in combination with a retaining strip for the warp strands carried by said endmost slat in the non-ventilating portion.

4. A woven screen of the kind described, comprising a plurality of transverse slats 40 held tightly together by warp-strands interlaced over the front and back of alternate slats, separating said slats only by the compressive thickness of the warp-strands, in combination with a plurality of slats held 45 spaced apart by the warp-strands separating said slats by one or more turns constituting a spacing greater than the thickness of said warp strands.

In testimony whereof, I have signed my 50 name to this specification, in the presence of two subscribing witnesses.

AZEL CLARENCE HOUGH.
